RAIL ANCHOR AND SPIKE HARNESS

Adam Gehnert, Marsh, Mont.

Application May 21, 1947, Serial No. 749,525

4 Claims. (Cl. 238—375)

1

This invention relates to a rail anchor and spike harness.

It is an object of the present invention to provide a simple means for anchoring a rail spike against displacement from the tie and outwardly from the rail wherein the same can be easily inserted over the rail bottom flange and wherein a minimum amount of material extending inwardly along the flange from one side of the tie is used.

Other objects of the present invention are to provide a rail anchor and spike harness which is of simple construction, inexpensive to manufacture and convenient to use.

For other objects and for a better understanding of the invention, reference may be had to the following detailed description taken in connection with the accompanying drawing, in which:

Fig. 1 is a top plan view of a rail with my rail anchor and spike harness applied to the opposite sides of the rail and to the bottom flange thereof and extending inwardly from opposite sides of the tie over the spikes to be retained within the tie and against displacement from the rail.

Fig. 2 is a side elevational view of the rail and looking upon one end of a tie, and upon the anchor and spike harness of the present invention.

Fig. 3 is a cross-sectional view taken through the rail and on line 3—3 of Fig. 2, and upon the rail anchor and spike harness of the present invention.

Fig. 4 is an enlarged side elevational view of the rail anchor member.

Referring now to the figures, 10 represents a tie over which a rail 11 is extended. Below the rail is a plate 12 with which bottom flange 13 of the rail engages.

Spikes 15 are extended downwardly through the plate 12 and are driven into the tie 10 so that their heads 16 extend over the bottom flanges 13 of the rail 11. In order to retain the spike 15 in place, I have provided a spring steel element 17 having a portion 18 adapted to extend over the head of the spike from one side of the tie and adapted to fit upon the top face of the flange 13. The spring steel strip 17 or spike retainer is curved upwardly as indicated at 19 so that its outer end 20 will engage the top face of the flange and is provided with a central portion 21 adapted to fit within a recess 22 in an upwardly and inwardly extending hook formation 23 of a rail anchor 24, Fig. 4. The rail anchor has a hook formation 25 which will fit the opposite bottom flange of the rail. The part 18 of the spring strip

2

or spike retainer has a downwardly bent end 22" which will engage the top surface of the flange 13 so as to space the portion 18 above the flange surface to accommodate the spike head 16.

5 The rail anchor part 24 has a wide flange 27 throughout the extent which it engages the rail and also in the portion or hook formation 23 which extends over the spike retainer 17.

The portion 21 of the spike retainer is indented throughout the length of the recess 22 and will be brought to bear within the recess whereby to depress the portion 21 of the retainer. The sharp ends 20 and 22' will prevent the spike retainer 17 from creeping along the flange 13.

10 In order to prevent transverse adjustment of the anchor 24 once it has been mounted upon the bottom flange of the rail there is provided a shoulder 29 adapted to abut one side edge of the bottom flange 13.

15 While various changes may be made in the detail construction, it shall be understood that such changes shall be within the spirit and scope of the present invention as defined by the appended claims.

20 I claim:

1. A rail spike retaining arrangement comprising a spike retainer element formed of spring metal and having a portion adapted to extend along the flange at the bottom of a rail and over the head of a spike driven into a tie and engaging with the bottom flange of the rail, said spike retainer being bound and having its ends bent downwardly for dig-in engagement with the top surface of the flange to prevent creepage thereof on the flange and a central indented portion, a rail anchor element fitted under the bottom flange of the rail and having a hook formation adapted to extend upwardly from the side edge of the flange and over the indented portion of the spike retainer to retain the retainer in a tightly flexed condition upon the top surface of the bottom flange.

2. A rail spike retaining arrangement as defined in claim 1 and said rail anchor formation adapted to extend over the spike retainer having a recess into which the spike retainer indented portion is extended whereby to positively lock the spike retainer against lateral displacement upon the top surface of the rail flange.

30 3. A rail spike retaining arrangement as defined in claim 1, and said rail anchor having a shoulder at the end of the same to which the spike retainer is attached adapted to cooperate with the edge of the bottom flange whereby to lock the spike retainer against lateral displace-

35

ment in one direction and toward the center of the rail.

4. A rail spike retaining arrangement as defined in claim 1, and said rail anchor formation adapted to extend over the spike retainer having a recess into which the spike retainer indented portion is extended whereby to positively lock the spike retainer against lateral displacement upon the top surface of the rail flange, and the portions of the rail anchor engaging with the rail and with the spike retainer and over the recess thereof being wider than the external portions whereby to provide a large surface contact of the rail

anchor with the bottom flange of the rail and with the spike retainer indentation.

ADAM GEHNERT.
